UNITED STATES PATENT OFFICE.

ROBERT H. COWDERY, OF GENEVA, OHIO.

GOLF CLUB.

Application filed March 20, 1922. Serial No. 545,333.

The present improvements, relating as indicated to golf clubs, have more particular regard to an improved construction whereby the shaft and head are made of one integral piece of metal, preferably steel. I am aware that it has heretofore been proposed to make the shafts of golf clubs of metal, but in all such prior attempts, the head has been fashioned separately and so requires to be secured to the end of the shaft which is not satisfactory either from the standpoint of ease of manufacture or durability under conditions of use to which golf clubs are subjected. In all such prior constructions, moreover, the shaft has been made of tubular form, or in shapes with holes or slots punched therein which not only gather dirt and rust but also produce a whistling noise very unpleasant to golfers, whereas according to my improved design said shaft is of solid cross-section, the necessary rigidity and strength being secured by fashioning the same with integral ribs of such form and disposition as to require a minimum amount of metal in order to provide the necessary strength. Other features of improvement will be found in the construction of the handle and in various details, all as will be hereinafter fully described in the specification and particularly pointed out in the claims, the annexed drawings and the following description setting forth in detail certain means and one mode of carrying out the invention, such disclosed means and mode illustrating, however, but one of various ways in which the principle of the invention may be used.

In said annexed drawings:

Fig. 1 is a side elevational view of my improved club complete as finally assembled; Figs. 2 to 8, inclusive, are transverse sections thereof on a somewhat larger scale, the planes of the sections being indicated by the lines 2-2, 3-3, 4-4, 5-5, 6-6, 7-7 and 8-8, respectively, on Fig. 1; Fig. 9 is a longitudinal central section of the handle of my improved golf club; Fig. 10 is a broken perspective view of a portion of the shaft that lies within the handle; Fig. 11 is a broken perspective view of the head; Fig. 12 is a central section similar to that of Fig. 9 but showing a modified construction of handle; Fig. 13 shows in perspective a bar of metal from which I fashion as

one integral piece the shaft and head of my improved golf stick; Fig. 14 shows such bar after the initial step in the manufacture of the club whereby the head is formed; Fig. 15 is a more or less diagrammatic view of a set of rolls designed for use in fashioning the shaft from such bar; Fig. 16 is a side elevational view of the finished shaft and head integral therewith; and Figs. 17 and 18 are views similar to Figs. 3 and 4 but illustrating a modification in construction.

As already explained, one of the distinguishing features of my improved golf club is the fashioning of the shaft 1 (see Fig. 1) and head 2 integrally out of one piece of metal, such shaft extending entirely through the handle 3.

Since the detail construction of the shaft can be most readily explained in connection with my improved method of making the same, it will be noted that as shown in Figs. 13, 14 and 15, I start with an elongated, preferably rectangular, piece 4 of steel or equivalent metal. The first operation then consists in striking up from such piece of metal by means of suitable forging dies the head 2 which may take on various forms, depending upon the particular style of club involved. This head as thus struck up will lie at approximately the same angle relatively to the remaining body of the piece 85 of metal 4 as it is intended it should have relatively to the axis of the shaft. The particular cross-sectional shape of the original blank need not, of course, be rectangular as just described but may be circular or oval, 90 and the head may be perfectly formed at once as a part thereof. The shaft in either case is then fashioned from such remaining body of metal by subjecting the same to successive rolling operations, i. e., by passing such body between rolls 5, 5, of the type illustrated in Fig. 15, whereby such body is lengthened and at the same time given the cross-sectional shape in its various parts illustrated in Figs. 4, 5, 6 and 7. Directly 100 adjacent the head for a short distance, as indicated at 6 in Figs. 1 and 16, said shaft will preferably be left of approximately circular cross-section, as shown in Fig. 7, and this portion will be most conveniently 105 formed in the forging step along with the head. For the remainder of its length the shaft is made of tapering cruciform section,

the taper being either continuous from the end adjacent the head to the opposite end or such taper may extend from each end to approximately the mid-point of the shaft.

- 5 It will be observed that, as shown in Fig. 11, I preferably align the head 2 with one of the ribs 7 that form a feature of the shaft due to its cruciform cross-section, as aforesaid.
- 10 Furthermore, those portions 7^a of the ribs lying within the handle 3 are preferably not as high as in the main body of the shaft, more or less abrupt shoulders 7^b marking the location of the inner end of the handle.
- 15 Such inner end is preferably formed by means of a washer 8 that abuts against these shoulders and one or more similar washers 9 are secured at the extreme outer end 10 of the shaft, such end being made of reduced circular form to receive such washers 9. The portion of the shaft thus lying between washers 8 and 9 is preferably first encased in a wooden core formed of strips 11 interiorly fitted to the rib portions 7^a and presenting exteriorly an approximately cylindrical surface. Over such wooden core is then applied a material adapted to provide a satisfactory grip, such grip portion of the handle, as illustrated, consisting of a 20 plurality of leather rings or washers 12 that tightly fit such core and are closely pressed together between washers 8 and 9. Such grip portion will be given a slightly tapering form, as shown in Figs. 1 and 9, and 25 will be polished to the proper degree of smoothness.

It will be understood that in place of a grip thus composed of leather washers, I may employ a handle composed wholly of 30 wood or of a plastic material capable of hardening after it has been molded. Thus, for example as shown in Fig. 12, the handle may be formed of vulcanized rubber or of any one of the several condensation products of phenol that are known on the market under various trade-names. It will be desirable, however, where such a plastic material is employed to form the handle, that it be applied around a wooden core, the latter giving to this portion of the club a rigidity that is desirable not only to prevent cracking or breaking of such material, but also from the standpoint of the user. I have found that a shaft of the form and 35 construction hereinbefore described possesses all the desirable characteristics, in the way of resiliency, lightness, etc., of the wooden shafts which have heretofore been almost universally employed in making golf sticks. However, by using properly tempered steel I obtain a degree of strength that far exceeds that of any such wooden shaft and in fact renders the shaft practically unbreakable. The head being integrally fashioned from the same bar of metal

as the shaft, it is of course impossible for it to become loose and the section of the shaft adjacent the head is such that there is little or no danger of the head being twisted relatively to the shaft. Finally, the manufacture of my improved shaft with integral head involves relatively simple forging and rolling operations which present no particular difficulties and render it possible to keep the cost of a club made in accordance with 75 my invention within reasonable limits.

Instead of the shaft 1 being of cross-shaped section, as hereinbefore described, i. e. having four symmetrically disposed ribs, said shaft may obviously have a greater or 80 lesser number of ribs and still retain the desirable features of lightness and strength which have been pointed out. Thus in Figs. 17 and 18 is shown a shaft of three-ribbed or triangular section, which has been found 85 well suited to give the exact weight desired and at the same time preserve a proper balance.

Other forms may be employed embodying the features of my invention instead of the 90 one here explained, change being made in the form or construction, provided the elements stated by any of the following claims or the equivalent of such stated elements be employed.

I therefore particularly point out and distinctly claim as my invention:—

1. In a golf club, the combination of a metallic shaft, and a head integral therewith, said shaft being solid throughout with 100 integral, longitudinally extending solid ribs, and said head being fashioned out of the same piece of metal with said shaft.

2. In a golf club, the combination of a metallic shaft, and a head integral therewith, said shaft being solid throughout with 105 integral, longitudinally extending solid ribs, and said head being fashioned out of the same piece of metal with said shaft and aligned with one such rib.

3. In a golf club, the combination of a metallic shaft, and a head integral therewith, said shaft being solid throughout with two pairs of oppositely disposed, integral, longitudinally extending solid ribs, and said 115 head being fashioned out of the same piece of metal with said shaft.

4. In a golf club, the combination of a solid metallic shaft of gradually tapering form from one end to the other, and a head 120 integral with the small end of said shaft, said shaft having integral, longitudinally extending solid ribs of corresponding taper, and said head being fashioned out of the same piece of metal with said shaft.

5. In a golf club, the combination of a metallic shaft having longitudinally extending ribs, the portions of such ribs adjacent one end of said shaft being of reduced diameter; and a handle fitted to such end,

said handle comprising plural complementary wooden core parts surrounding and interengaging with the adjacent portions of such ribs, and a grip portion surrounding such core.

6. As an article of manufacture, a metallic shaft for golf clubs comprising a solid

portion gradually diminished in transverse cross sections as the club head end of the shaft is approached, such transverse cross sections being substantially star-shaped. 10

Signed by me this 15th day of March, 1922.

ROBERT H. COWDERY.
